TERMINAL BANK

William Francis Smith, Brooklyn, N. Y., assignor
to International Standard Electric Corporation,
New York, N. Y., a corporation of Delaware

Application January 14, 1947, Serial No. 721,977

2 Claims. (Cl. 173—324)

1
The present invention relates to bank strips and especially to such strips as are used in automatic telephone systems.

Heretofore it has been proposed to make a bank strip wherein sets of transverse terminal pins are secured in the sides of a molded frame of, for example, suitable plastic insulating material, a separate thin plate of insulating material is placed across each of said sets of terminal pins and perforated at predetermined points, and longitudinal wires are electrically connected to selected terminal pins. A bank strip of this general nature is disclosed and claimed in the prior application Serial No. 525,853, filed March 10, 1944, now abandoned.

An important object of the present invention is to provide a novel and advantageous construction of bank strips containing transverse terminal pins or such terminal pins in connection with wires perpendicular thereto and constituting multiple connections for the pins.

Another important object of the invention is to provide a novel and advantageous method of making bank strips embodying features of the present invention.

Another object of the invention is to provide novel and advantageous terminal pin strips adapted for manufacture in quantity and for maintaining terminals of said pins rigidly and accurately in position.

Another object of the invention is to provide novel and advantageous bank strips comprising a plurality of terminal pins, a unitary body of insulating plastic material having opposite sides in which said terminal pins are embedded with their ends protruding, one or more panels or plate portions over the central portions of said terminal pins with openings exposing said terminal pins at desired locations and means for positioning longitudinal wires over said openings to enable electrical connections therethrough of said wires to said pins.

Another object of the present invention is to provide a terminal strip comprising terminal pins and molded thereon a complete unitary body of insulating plastic material with insulating panel parts over the pins and having openings where connections are to be made.

Another object of the invention is to provide a novel and advantageous bank strip structure wherein groups of selector pins are embedded in the sides of a unitary body of insulating material such as a suitable plastic, and thin insulating parts of said body extend over the intermediate portions of said pins, and have elongated in-

2
clined openings over the crossings of successive pins and longitudinal wires where said wires are to be electrically connected to the pins, said body having means for positioning said longitudinal wires with respect to said selector pins.

Another object of the invention is to provide a bank strip structure whereof the body may in a single operation be molded in complete form on the terminal pins, ready for the application of the longitudinal wires and the establishment of electrical connections thereof to the pins.

An advantageous feature of the present invention is that a plurality of bank strips can be molded on a group of wires usable for selector pins and the wires may be then cut between said bank strips, thus leaving units ready for application of the longitudinal wires and connection thereof to said selector pins.

Other objects, features and advantages will appear upon consideration of the following detailed description and of the drawings, in which:

Fig. 1 is a top plan view of a bank strip in horizontal position, said bank strip containing transverse terminal pins, but being without wires connecting said selector pins in multiple;

Fig. 2 is a section along the line 2—2 of Fig. 1;

Fig. 3 is a fragmentary bottom view of the left end of Fig. 1;

Fig. 4 is a section taken along the line 4—4 of Fig. 1;

Fig. 5 is a section taken along the line 5—5 of Fig. 1;

Fig. 5a is a section of a deformed part of a selector pin, said deformed section being embedded in the body of said strip;

Fig. 6 is a view similar to Fig. 1, but on a larger scale and broken away at its center, showing the longitudinal wires in position thereon and held by the plastic at the ends of the strip, said wires being electrically connected to corresponding terminal pins;

Fig. 7 is a section taken along the line 7—7 of Fig. 6; and

Fig. 8 is a section taken along the line 8—8 of Fig. 6.

One bank strip or terminal strip of the invention is illustrated in Fig. 1. This strip comprises a body 10 including a frame having sides 11 and 12, ends 13, and connections between said sides 10 comprising one or more panels 14 and cross pieces 15 which may be of different widths. Secured in the sides 11 and 12 are transversely arranged terminal pins 16 which project outwardly from said sides. Said body is made of insulating material, preferably molded plastic as for example

polystyrene. The terminal pins are rigidly secured to said sides by being molded therein. Each pin is also deformed at a point where it passes through one of the sides so as to enable the pin to be held firmly against longitudinal and rotational movement. For example each pin 16 may be deformed by providing it with one or more flat portions 16a positioned to be embedded in the sides 11 and 12 of the frame.

As shown the terminal pins 16 are round in cross-section except where deformed, and are arranged parallel to each other transversely of the frame. The terminal pins may be made of any suitable conducting metal, and are preferably made of Phosphor bronze. Any desired number of these pins may be used, but as illustrated, there are thirty-two pins 16 and these (Fig. 1) are arranged in groups, A, B, C and D, eight pins in each group. Inasmuch as the pins 16 project from the sides 11 and 12, of said body, both ends may be used for making contact with the moving brushes of a selector switch or a plurality of such switches when the device is used in automatic telephone equipment. When used for such purposes, it is desirable to have the ends of the pins in alignment, and very accurately positioned.

The bank strip thus far described would be useful in automatic telephone apparatus. However, it would have a much greater range of use if groups of the selector pins were connected in multiple with other groups and with groups of pins in similar bank strips. For such multiple connections use may be made of bare wires 17 of good conducting material such as copper, which extend longitudinally of the bank strip and are longer than the body 10. These wires 17 are positioned over the central part of said body 10 by providing deep longitudinal grooves 18 in raised portions of said ends 13. These grooves 18 are arranged and spaced to position the wires 17 parallel to each other and at even spaces across the central part of said body 10. Said panel or panel portions 14 and cross pieces 15 are integral with each other and have at the face toward said wires 17 a common plane surface depressed somewhat below said sides 11 and 12 and ends 13. In said common plane surface within the frame are shallow grooves 18a to receive the lower parts of wires 17. Said panel portions 14 also enclose one-half of each of the selector pins between the sides 11 and 12.

In order to electrically connect the wires 17 to said selector pins 16 it is necessary to expose parts of the selector pins where electrical connections with wires 17 are to be effected. As shown in Fig. 1, the crossings of pins 16 and wires 17 where electrical connections are to be made are in lines inclined with respect to the strip and in each group of eight crossings the similar groups of four are separated by one of the cross pieces 15 and therefore the lines of such crossings are offset with respect to each other. The exposure of the crossings of the wires 17 and the selector pins might be made through separate openings, but in view of the unitary structure of the body 10 it is much more convenient in molding such body to have slots 19 instead of separate openings.

The wires 17 are welded or otherwise electrically connected to the pins 16 where they cross, the connections being made through said slots 19. Because of the close proximity between the wires and pins a slight deformation of either or both will produce contact thereof through the slots in the panel portions 14. It will be seen that

one of the wires 17 is attached to the first of the pins 16 in each group A, B, C, and D, and that each of the other wires is attached to a corresponding pin in each group. In this way the groups are connected in multiple by the longitudinal wires 17.

The wires 17 should be kept stretched over the body 10 and this result may be obtained while holding the wires in stretched condition by heating the thermoplastic material in areas across said ends 13 and pressing the plastic material around the wires 17 in said grooves 18 sufficiently to hold them in position. In such heating and pressing of the plastic material, grooves 19a are produced in said ends 13.

It may be desirable, especially in automatic telephone apparatus, to have a number of the units of Fig. 6 connected together in a string as disclosed in said application Serial No. 525,853, filed March 10, 1944. Such units may be spaced apart a short distance and the wires 17 between them may be insulated in any suitable manner as by coating the same with an insulating lacquer.

The welding of the wires 17 to the selector pins 16 may be effected by apparatus designed for that purpose. To adapt the strip for use in such welding apparatus, a central cross-piece 15 is provided with a slot 20 of a length substantially equal to the width of the panel portion. In the welding machine this slot permits the projection therethrough of a comb which serves to position the strip and the wires 17 thereover. The body 10 may also be provided with transverse slots 21 in end extensions 22 to accommodate in each slot one member of cutting means for severing the wires 17. It should be understood that in use the bank strips are arranged vertically and flat against each other with the side edges in alignment.

The article illustrated in Figs. 1, 2 and 3 constitutes a selector pin strip 23 and the article illustrated in Fig. 6 is a completed bank strip 24.

The bank strips may be used singly or in strings connected by wires 17 as disclosed in said application Serial No. 525,853, filed March 10, 1944. As indicated in Figs. 1 and 6, each end of each selector strip 23 and each bank strip 24 is reduced in width to provide shoulders 25 and each end of reduced width is provided at opposite edges with projections 26 of the general shape of isosceles triangles. These projections 26 are designed to fit in grooves in suitable frame members. In this way the strips are aligned.

The end extensions 22 are not found in said prior application and some changes in the strip-holding frame may be made. As shown in the lower left-hand corner of either Fig. 1 or Fig. 6, the corresponding extension 22 is cut out at one side leaving a shoulder 27 extending inwardly to an edge 28. If a frame member (not shown) be shaped to engage shoulder 25, projection 26, shoulder 27 and edge 28 at one corner of the bank strip, and other frame members (not shown) be shaped to fit along a straight edge 22a of the extension 22, the first mentioned frame member would not receive any corner of the strip but the one having the shoulder 27 and the edge 28. The construction just referred to assures proper placing of the strips in a frame.

The method of making the selector or terminal pin strip 23 illustrated in Figs. 1, 2 and 3, may be carried out in suitable apparatus of which a preferred form of molding apparatus is disclosed and claimed in my companion application Serial No. 730,969, filed February 26, 1947. The method

of making the bank strip 24 of Fig. 6 from the terminal pin strip 23, may be carried out in suitable welding apparatus of which a preferred form is disclosed and claimed in my companion application Serial No. 727,802, filed February 11, 1947, now U. S. Patent No. 2,474,285 which issued on June 28, 1949. These methods while complete in themselves are parts of a main method of making the final bank strip 24.

In making the terminal strip 23, wires of suitable cross-section and composition for the formation of terminal pins 16 therefrom, are advanced through a molding zone step by step with dwells therebetween and during each dwell at least one body 10 of insulating material is molded on said wires. The molded material is then moved out of the molding zone and at the next dwell another molding operation is effected. These steps are repeated until it is necessary to stop, as for example when substantially the full lengths of the wires have been used. During said dwells the wires may be cut between molded bodies 10 which have been advanced a plurality of steps.

The wires from which the terminal pins 16 are cut are usually supplied in close wound masses so that the wires are set in close coils of small radius. Before molding bodies 10 on said wires, these wires are straightened by running them through straightening apparatus. For convenience in feeding the terminal-pin wires through a molding zone or machine, they may be coiled on reels of substantial diameter. The wires may be drawn from the reels by means located between the reels and the molding zone, and the strips beyond the molding zone may be advanced by suitable means to draw newly formed terminal-pin strips from the molding zone. Retrograde movement of the wires and strips may be prevented by means at the outlet side of said molding zone.

In the second part of the main method; a finished strip 23 is placed against wires 17 so that the wires are seated in the various grooves 18 in the ends 13 and grooves 18a in the panel 14. Then with the strip 23 in the welding zone, welding of the wires and pins may be effected at crossings thereof along said slots 19, and plastic material at the ends 13 may be softened by heating and passed down into grooves 18. The welding may be effected in a plurality of welding operations, thus making it possible to have simultaneously formed welds separated by substantial spaces.

After completion of the welding for a given strip, the strip and the multiple-connection wires connected thereto are drawn out of said welding zone and another strip 23 is drawn into the welding zone. During the welding for the second strip, the first-mentioned strip may be in a testing zone where all of the crossing welds are tested, preferably simultaneously. There is also a zone wherein the wires are bent to provide slack between strips. At another point along the path of travel of the strips, the wires 17 are cut where desired to provide individual strips or a plurality

of strips. Said strips may then be assembled for mounting in terminal banks. Of course the testing of the welds may be effected after cutting off single bank strips or a plurality of connected bank strips.

It should be understood that various changes may be made and certain features used without others, without departing from the true scope and spirit of the invention.

10 What is claimed is:

1. A bank strip comprising a flat unitary frame of insulating material having a pair of spaced edges, a plurality of transverse terminal pins having portions thereof embedded in said edges and extending a predetermined distance beyond each edge, a panel insulating said plurality of terminal pins on one side of said frame, said panel being formed integral with said frame and partially surrounding said plurality of pins, a plurality of wire-receiving grooves being provided in said panel on the side opposite said terminal pins and being insulated therefrom by a portion of said panel; said panel being further provided with diagonally extending slots adapted to expose predetermined pins at every crossing of a pin by a wire receiving groove, said unitary frame having ends formed integral with said panel and substantially flush thereto, said wire receiving grooves extending through said ends, an extension being provided on each end below the level of said wire receiving grooves for securing wires in said grooves and means formed integral with said frame for mounting said bank strip.

2. A bank strip as claimed in claim 1 wherein said mounting means comprises protruding portions at each corner of said frame and said frame is notched immediately adjacent to said protruding portions.

40
